UNITED STATES PATENT OFFICE.

BENJAMIN BOLLINGER AND GEORGE G. NODLE, OF NEW BERLIN, OHIO.

IMPROVEMENT IN KNITTING-MACHINES.

Specification forming part of Letters Patent No. 82,281, dated September 22, 1868.

To all whom it may concern:

Be it known that we, BENJAMIN BOLLINGER and GEORGE G. NODLE, of New Berlin, in the county of Stark and State of Ohio, have invented new and useful Improvements in Knitting-Machines; and we do hereby declare that the following is a full, clear, and exact description of our invention, reference being had to the accompanying drawings, forming a part of this specification, and to the letters of reference marked thereon, of which drawings—

Figure 1 is a plan of our improvement applied to the Isaac W. Lamb knitting-machine. Fig. 2 is a side view of the same. Fig. 3 is a cross-section of the same. Fig. 4 is a view of a needle. Fig. 5 are side view and plan of the spring used in connection with the needle. Fig. 6 is an end view of the same.

Our invention relates to that class of knitting-machines where the widening and narrowing of the fabric to be knit are effected by throwing one or more of the needles into or out of the reach of the action of the operating-cams, which move the needles when working, of which the knitting-machine patented by Isaac W. Lamb, September 15, 1863, and October 10, 1865, affords a good example, said improvements consisting of an improved spring, which is used in connection with the knitting-needle, the two working together to secure the bringing of the knitting-needle in a correct position to be operated on by the operating-cams when the needle is in use, and serving to insure its being kept down out of the way when not in use.

To enable others skilled in the art to make and use our invention, we will proceed to describe its construction and operation.

In the drawings, which form a part of this specification, only the main portion of the machine is shown, as it is the only part directly connected with our improvements. The inclined sides A A of the body of the machine are connected by the triangular ends B, and have the space C between their upper edges, down through which passes the work or fabric being knit. The needles F rest in slots in these sides A, and are held in said slots by the wire D and the scale E, or their equivalents, as shown. The scales E are thin pieces of metal, arranged on the sides A, as shown, and

have the numbers 1, 2, 3, and so on, arranged on them, as shown, these commencing at the center of the machine and running out toward each end.

As the middle needle at the back of the machine (shown at 1 at the top of Fig. 1) corresponds to a space on the front of the machine, or to two needles on said front, so there are two No. 1's on said front, as shown; or, in other words, as there is always one less needle at work on one side of the machine than on the other, the numbers are accordingly one less on one side than on the other. The use of this scale of numbers is readily seen. If it be required to knit a piece of work ten stitches wide, the needles 1 to 5 are put at work on each side, and the necessary number of stitches is made, and likewise for any other even number. To set the needles for an odd number of stitches—as, for instance, seven—put needles 1 to 4 and 1 to 3 at work on each side, having the same number of stitches on each side of the center.

It is also readily seen that the numbers might be stamped, cast, or engraved, or otherwise attached to the sides A A at the side of each needle, instead of having a scale, E, of metal, as shown, or that the Nos. 1 might begin at one side of the center of the machine, if desired, but that this last plan would be objectionable, as the scale would not then apply to the full working capacity of the machine.

The needles F have the hook P at the upper ends, with such other devices as are needed to aid in the operation of knitting, and have the arm G, which is acted on by the operating-cams to produce the movement of the needles. The needle is extended back of the arm G, as shown at H, and when the needle is not working this part H projects beyond the side A, as seen in Figs. 1 and 3.

A spring, K, is arranged under the side A by being inserted in the block L, or in any other suitable manner, and the bent portion N of this spring has a rounding depression made in it, and has the top cut in the form seen in Fig. 6. This semicircular concavity at the end of the part N bears against the part H of the needle F when said needle is pushed down, so as to be out of the reach of the operating-cams, and holds the needle from working up.

The part H of the needle F is made of such

a length that when the needle F is drawn up, and the lower end of the part H rests against the part N of the spring K, which flies up at the end of the part H by reason of the action of the spring K, as soon as the needle F is drawn up the arm G shall be in the correct position for being acted upon by the operating-cams.

The rounding depression in the side of the part N of the spring K serves to guide the end of the needle F H down on the part N, and to insure the setting of the spring K, which would not be done were the end of the part H of the needle F H to slip off the spring K N, which it would do were it not for this rounded depression.

It is readily seen that this arrangement of the needle and spring insures the bringing of the arm G into the correct position for being acted upon by the operating-cam, and prevents the said arm from being broken off or bent, or any injury being done to the operating-cam or side A by the side of said cam striking the

arm G in any place except the proper one, and that the needles F H, being held down by the springs K N, are not liable to work up and come in contact with the operating-cams when thrown out of their working position.

Having thus fully described the nature of our improvements, what we claim as new, and desire to secure by Letters Patent, is—

The spring K N, constructed as described, in combination with a needle of a knitting-machine, substantially in the manner and for the purpose herein specified.

As evidence that we claim the foregoing we have hereunto set our hands in the presence of two witnesses this 5th day of March, A. D. 1868.

BENJAMIN BOLLINGER.
GEORGE G. NODLE.
